UNITED STATES PATENT OFFICE.

DAVID TAYLOR, JR., OF ST. FRANCISVILLE, LOUISIANA, ASSIGNOR OF ONE-HALF TO WILLIAM R. PERCY, OF ST. FRANCISVILLE, LOUISIANA.

GRUBBER.

No. 853,840.

Specification of Letters Patent.

Patented May 14, 1907.

Application filed July 20, 1906. Serial No. 327,034.

To all whom it may concern:

Be it known that I, DAVID TAYLOR, Jr., a citizen of the United States, and a resident of St. Francisville, in the parish of West Feliciana and State of Louisiana, have invented a new and Improved Grubber, of which the following is a full, clear, and exact description.

This invention relates to grubbers, and is particularly useful in connection with devices of this character intended for use in removing railroad ties and the like.

The object of the invention is to provide a grubber which is simple, strong and durable, and which is peculiarly adapted for use in connection with hard, rocky ground or shale.

A further object of the invention is to provide a device of the character described which may be used as a grubber, and which may also be used for removing the tie from underneath the rails after the same has been freed from the earth or ballast surrounding it.

A still further object of the invention is to provide a grubber which may be used as an ordinary crowbar as circumstances require.

The invention consists in the construction and combination of parts to be more fully described hereinafter and particularly pointed out in the claims.

Reference is to be had to the accompanying drawings forming a part of this specification, in which similar characters of reference indicate corresponding parts in all the figures, in which

Figure 1 shows a perspective view of a section of railroad track showing my invention in operation; Fig. 2 is a transverse section of a railroad track showing my device in use for removing the tie; Fig. 3 is a side elevation of my invention in use for removing a post from the ground; Fig. 4 is a similar view showing my invention in use in a different manner for removing a post; Fig. 5 is a side view showing an end of my device in longitudinal section; and Fig. 6 is a perspective view of a detail of my invention.

Referring more particularly to the drawings, I provide a lever bar 1, which may be of substantially rectangular section or of any suitable form. The upper end 2 of the bar is formed into a sharp point and has, near the point, a hook 3 rigidly mounted in a proper opening in the bar and with its end riveted in

place. The bar, as well as the other parts of the invention, may be formed of steel or other material suitable for the purpose. At the opposite end of the bar which is given a slightly curved form, is mounted a pointed blade or shovel 4, with the point extending somewhat beyond the end of the bar. The end 5 of the bar is beveled and tapered to a point with a flat side in contact with the back of the shovel. The shovel is removably attached to the bar by means of screw bolts 6 located in suitable openings in the shovel and the bar. Attached rigidly upon the bar, near the shovel and somewhat above the same, is a hook 7 similar to the hook 3 and attached in the same manner. I prefer to have the hooks 3 and 7 project from the bar respectively on opposite sides thereof.

Removably mounted upon the bar, near the end which bears the shovel 4, is a stirrup 8 constituting a removable bracket. The stirrup 8 has a flat face 9, and ends 10 inwardly disposed and separated a distance slightly greater than the diameter of the bar, said ends being provided with a series of openings 11. Each opening on one end is substantially opposite to an opening on the other end of the stirrup. A suitable hole is provided through the bar, and by means of a bolt 12 passing through opposite openings in the stirrup ends and the hole in the bar, the bracket is pivotally mounted upon the bar. A chain 13 is provided of suitable length and having at one end a flat hook 14, which is adapted to engage with the head of a rail, or any other anchoring object, as shown most clearly in Fig. 2. The chain is adapted to be attached to either of the hooks upon the bar, and its links are of such size that it may be attached to these hooks by means of one of its links, thus permitting any desired length to be secured by the operator.

In digging away the earth or ballast from around a tie, for the purpose of removing that tie, the mode of operation is as follows: The hook 14 of the chain is caught upon the head of a rail and the point of the shovel is inserted into the ground, the grubber being placed at the whole length of the chain from the rail to which the chain is anchored. On pulling at the upper end of the bar in a direction away from the rail to which the chain is anchored, the shovel will be forced into the ground by the lever action of the bar, ful-

2

crummed by means of the chain and the hook directly above the shovel. When the shovel has penetrated a certain distance into the ground through this leverage, the bracket 8 will rest against the ground and prevent further penetration, while, at the same time, providing a new fulcrum for the bar at that point. As the downward pressure upon the bar is continued, the bar will pivot about this new fulcrum presented by the bracket 8, and the shovel will therefore, be forced upwardly from the earth, bringing with it a quantity of the same and breaking it up into fragments as the operation is repeated.

15 It will be understood that this invention is not intended for the removal of the earth, but merely for the breaking up of the same into small parts. It is especially useful in connection with ground which is particularly hard packed, or containing stones and the like. By means of this device, great leverage may be exerted and the operation effected with little physical exertion. If the ground is particularly hard the shovel 4 may 20 be removed and the pointed end of the bar used to break up the ground.

25 When the earth has been dug away from around the tie and it is desired to pull the tie out from under the rails, the rail spikes are removed in the usual manner, and the pointed end 2 of the bar is then driven into the wooden tie, the chain 13 being attached to the hook 3, while the chain hook 14 is caught upon the rail head in the same manner as before. By pulling upon the shovel end of the 30 bar away from the rail, the leverage about the hook 2, which acts as a fulcrum, will force the tie along underneath the rail, and the operation may be repeated until the tie 35 has been removed.

40 The bar 1 may be used for many purposes for which the ordinary crowbar is used at present, the pointed end making it particularly adaptable for this.

45 The device may be used for pulling stumps, as shown in Fig. 3, the bar being rested upon any suitable object to serve as a fulcrum, while the chain is secured about a post and attached to a hook upon the bar.

50 By pulling downward upon the end of the bar opposite to that which carries the chain, the leverage will tend to pull the stump upwardly out of the ground. It may be used for the same purpose in a more simple manner by driving the pointed end into the wooden post, using the hook as a fulcrum by resting it upon the ground or on any suitable object, and using the bar as a lever in the ordinary manner.

60 The bracket 8 is adjustable by means of the series of bolt holes in its ends, and the distance to which the shovel can penetrate the ground can be regulated by increasing or decreasing the effective length of the bracket by inserting the bolt 12 through different 65 openings 10 in the bracket 9.

Having thus described my invention, I claim as new and desire to secure by Letters Patent:

1. A grubber, comprising a bar having a 70 shovel, means for removably attaching said bar to an anchor, and a bracket pivotally mounted upon said bar and adapted to rest upon the ground to act as a fulcrum for said bar.

75 2. A grubber, comprising a bar having a shovel, means for removably attaching said bar to an anchor, and a bracket on said bar adapted to limit the penetration of said shovel into the earth and to act as a fulcrum 80 for said bar.

3. A grubber, comprising a bar having a beveled, tapered end, a shovel removably mounted near said end, means for removably attaching said bar to an anchor, and a bracket 85 on said bar having a flat face adapted to rest upon the ground.

4. A grubber, comprising a bar with pointed ends, a shovel removably mounted upon said bar near an end thereof, a hook on said 90 bar, a chain adapted to be removably attached to said hook, and means for anchoring said chain.

5. A grubber, comprising a bar with pointed ends, a shovel removably mounted upon 95 said bar near an end thereof, a hook on said bar, an anchor, a chain adapted to join said hook with said anchor, and a bracket adjustably mounted on said bar adapted to rest upon the ground when said shovel is driven 100 thereinto.

6. A grubber, comprising a bar having pointed ends, a shovel removably mounted near an end of said bar, a stirrup adjustably mounted upon said bar and constituting a 105 bracket adapted to rest upon the ground, a plurality of hooks rigidly attached to said bar, and a chain having an anchoring hook and adapted to be removably attached to one of said hooks.

110 In testimony whereof I have signed my name to this specification in the presence of two subscribing witnesses.

DAVID TAYLOR, JR.
